[57] CLAIM

The ornamental design for a combined attache case and detachable file folder, substantially as shown and described.

DESCRIPTION

FIG. 1 is a perspective view of a combined attached case and detachable file folder, showing my new design;

FIG. 2 is a front elevational view thereof;

FIG. 3 is a left end elevational view, partially in section, taken along the line 3.3 of FIG. 1;

FIG. 4 is a front elevational view with the case open and the folder removed; and

FIG. 5 is a rear perspective view showing the case in a closed condition.
